UNITED STATES PATENT OFFICE.

GEORGE F. COLE, OF OAKLAND, CALIFORNIA, ASSIGNOR OF THREE-EIGHTHS TO
JOSEPH G. McCALL, OF OAKLAND, CALIFORNIA.

DESIGN FOR AN ORNAMENTAL FIGURE FOR RADIATOR-CAPS OF AUTOMOBILES.

55,981.

Specification for Design.

Patented Aug. 10, 1920.

Application filed December 20, 1917. Serial No. 208,184. Term of patent 3½ years.

To all whom it may concern:

Be it known that I, GEORGE F. COLE, a citizen of the United States, residing in Oakland, county of Alameda, and State of California, have invented a new, original, and ornamental Design for an Ornamental Figure for Radiator-Caps of Automobiles, of which the following is a specification, reference being had to the accompanying drawings, forming part thereof.

The figure is a perspective view of an ornamental figure for radiator-caps of automobiles, showing my new design.

I claim:

The ornamental design for an ornamental figure for radiator-caps of automobiles, as shown.

GEORGE F. COLE.
